CLAIM

I claim the ornamental design for a motorcycle ornament, as shown and described.

DESCRIPTION

FIG. 1 is a perspective view of a motorcycle ornament, showing my new design;

FIG. 2 is a left-side elevational view thereof;

FIG. 3 is a right-side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines in the figures depict environmental matter and form no part of the claimed design.

The motorcycle ornament is shown on an enlarged scale in FIGS. 2-7.
